*Fig. 5**Fig. 4*

FIG. 1 is a perspective view of a combined door handle and lock housing set in accordance with an embodiment of my invention shown mounted on a door;

FIG. 2 is a front view of the embodiment shown in FIG. 1 shown mounted on a foreshortened door;

FIG. 3 is a top view of the embodiment shown in FIG. 1 shown mounted on a door;

FIG. 4 is a foreshortened right side view taken as indicated by the lines and arrows 4-4 in FIG. 2 shown mounted on a door; and

FIG. 5 is a foreshortened view partially in section taken as indicated by the lines and arrows 5-5 in FIG. 2 shown mounted on a door.

The shading employed does not connote actual appearance, but is an expedient to best illustrate the shape of the handle.

Portions have been foreshortened on the drawings for convenience of illustration.

The door shown in dash lines forms no part of the design and has been included for purposes of illustrating the environment only.

I claim:

The ornamental design for a combined door handle and lock housing set, as shown and described.
